UNITED STATES PATENT OFFICE.

JEAN LOUIS BAILLE, OF PARIS, FRANCE, ASSIGNOR TO SOCIÉTÉ: BAILLE-LEMAIRE-ET-FILS, OF PARIS, FRANCE, A CORPORATION OF FRANCE.

PLATE-CARRYING FRAME FOR PHOTOGRAPHIC APPARATUS.

Application filed February 6, 1923. Serial No. 617,370.

To all whom it may concern:

Be it known that I, JEAN LOUIS BAILLE, a citizen of the French Republic, residing at 26 Rue Oberkampf, Paris, France, have invented certain new and useful Improvements in a Plate-Carrying Frame for Photographic Apparatus, of which the following is a specification.

The present invention relates to a plate holder of the type in which the sensitive plate is carried by a plate carrier which is introduced and spring held in an outer case which is mounted on the photographic apparatus.

According to this invention, the plate carrier receives the sensitive plate between lateral slides with sufficient clearance to allow of the easy introduction of the plate, the sensitive face of the latter being then maintained always in the same plane, when it is introduced with its carrier into the outer case, by springs secured to the outer case and resting on the back of the plate through the perforations in the carrier. A construction of the invention is illustrated in the annexed drawings, in which:

Fig. 1 is a front elevational view of the invention,

Fig. 2 is a vertical transverse section taken on line A—A of Fig. 1,

Fig. 3 is a top plan view of the arrangement of the invention.

Fig. 4 is a horizontal sectional view taken on the line B—B of Fig. 2.

The holder comprises three distinct parts, namely the slide 1, the case 2 and the plate carrier 3.

The plate carrier 3 is in the form of a rectangular plate the longitudinal edges of which are bent at right angles to form opposed grooves 11 between which is inserted a sensitive plate 4.

The case consists of a plate-like body 2 which constitutes one wall while continuing therefrom are side walls 12 having inturned portions 12' which are opposed to each other in spaced parallel relation from the wall or body 2 while the terminals of the side walls are shaped to form opposed slides or grooves 13 which extend longitudinally of the case. In this connection it is to be noted that the portions 12' and side walls 12 provide grooves to accommodate the plate carrier which in turn houses the plate 4,

To load the holder, the sensitive plate is introduced through the end 8 in the plate-carrier which latter, in its turn, is slid in the grooves 12 into the case.

To prevent access of light to the case, the plate carrier has on both sides at its upper part 10 a velvet strip 5 one surface of which fits on the inner surface of the case when the plate-carrier is slid therein.

Besides, the upper edge 7 of the plate-carrier covers the case as indicated in Fig. 2 for forming a baffle.

Finally, the slide 1 is placed in position in the grooves 13 for closing the frame. At the end 8 of the plate-carrier 3 an incline has been provided; on the other hand, at the upper part of the case 2 the grooves 12 have been enlarged at 6. This incline and this enlargement are adapted to facilitate the insertion of the plate-carrier into the case.

Finally, the springs 4 secured to the case, Fig. 1, are so placed that they pass through the grooves 9 in the plate-carrier 3 when the latter is placed in the case so as to always project the sensitive plate forward in order that it may always be maintained in the same plane.

What I claim as my invention and desire to secure by Letters Patent is:—

1. In a plate-holder of the character described, a case, a carrier for insertion in the case and provided with opposed longitudinal grooves along the marginal edges adapted to receive the sensitive plate to allow of the easy introduction of the plate, springs secured to the back of the case passing through the carrier in order to maintain the sensitive face of the plate in a predetermined plane in the case, and means provided on the carrier and on the case to facilitate the easy introduction of the carrier into the case.

2. In a plate-holder of the character described, a case, a carrier removably engaged within the case provided with opposed longitudinal grooves along the marginal edges adapted to receive the sensitive plate with sufficient ease to allow introduction of the plate, springs secured within the case extending through and pressing against the back of the plate to maintain the sensitive face of the plate in a predetermined plane in the case, a slide removably engaged in the case between the carrier and the back of the case, and the lower portion of the plate

carrier and the ends of the plate-holder being reduced to facilitate the easy insertion of the plate carrier into the case.

3. A device of the character described comprising a case, including a body provided at the side edges and adjacent the open front, inner and outer longitudinal grooves, a plate carrier in back of which is provided longitudinal slots while the side edges in turn are formed of opposed longitudinal grooves adapted to receive a sensitive plate with sufficient clearance to allow of the introduction of the plate, the carrier being insertable within the inner grooves of

the holder, a slide engageable with the opposed outer grooves for enclosing the holder, springs secured to the back of the case and passing through the slots in the plate carrier and adapted to maintain the sensitive plate of the face in a predetermined plane in the holder, and a flexible strip secured transversely about the outer portion of the carrier and contacting with the case and the slide for preventing the entrance of light within the holder. 15 20 25

In testimony whereof I have signed my name to this specification.

JEAN LOUIS BAILLE.
